By: Fabel & Muller Atty's.

UNITED STATES PATENT OFFICE.

GEORGE A. KOHOUT, OF CHICAGO, ILLINOIS.

HOPPER-FEED MECHANISM FOR STOKERS.

Application filed August 29, 1921. Serial No. 496,265.

This invention relates to furnaces and more particularly to means for feeding fuel thereto. More specifically the invention relates to a hopper platform feed arrangement, whereby the fuel may be fed into the furnace mechanically and the fuel entrance openings may be closed after said fuel has been fed into the furnace.

It is a purpose of the present invention 10 to provide a furnace with a fuel hopper having a shelf-like portion upon which the fuel is adapted to rest and means operating over said shelf-like portion for moving the fuel off said shelf into the fire box.

15 It is a further purpose of the invention to provide a hopper having a shelf-like portion as pointed out above with an opening leading to the fire box which is provided with closure members that are adapted to be moved into and out of closing position as desired and which will effectually seal the opening to prevent the fire burning back into the hopper.

It is still a further purpose of the invention 20 to provide a hopper of the above mentioned character with a front wall that may be tilted so as to dump the fuel out of the hopper when it is desired to empty the same, and to provide for removal of the means for pushing the fuel off the shelf, from said shelf, when desired.

It is another object of the invention to provide a hopper feed furnace with a hand stoker having a plurality of pusher members for moving the fuel into the fire box, said pusher members being preferably of refractory material.

It is a further object of the invention to 25 provide a hopper feed device for a stoker adapted to automatically and continuously feed fuel thereto, said feed device being provided with pushers or plungers to accelerate the feeding of the fuel and insure a continuous supply of fuel to the furnace.

It is a still further object of the invention to provide plungers of the above mentioned character that can be operated either individually or simultaneously.

It is another purpose of the invention to 30 provide a fuel feed device of the above mentioned character in a furnace having a flat arch of refractory material at the throat of the furnace.

It is still another object of the invention to provide a hand stoker with means for

feeding the fuel into the furnace above the plane at which the coal is ordinarily fed, so as to permit piling of the fuel at the front end of the stoker for coking purposes.

It is also an object of the invention to 60 provide a hopper with a front wall forming plate held in place by two pairs of pivot members so that said plate is held rigidly in place when both pairs of pivot members are in operative position, that said plate can be swung on one pair of said pivots when the other pair is moved out of operative position and that can be removed when both pairs of pivot members are moved out of operative position.

70 Other objects and advantages of the invention will appear as the description of the accompanying drawings, showing one form that my invention may take, proceeds. However, I desire to have it distinctly understood that I do not intend to limit myself to the exact details shown or described, but that I intend to include as part of my invention all such obvious changes and modifications of parts as would occur to a 75 person skilled in this art and as would fall within the scope of the claims.

In the drawings:—

Fig. 1 is a longitudinal fragmentary section of a furnace showing the improved fuel feeding device applied thereto, in conjunction with a mechanical stoker; 85

Fig. 2 is a fragmentary front elevation partly broken away of the furnace shown in Fig. 1;

Fig. 3 is a fragmentary plan view of one of the closure members and the connections therefor; and

Fig. 4 is a similar view of a modified form of closure member.

90 Referring in detail to the drawings, the furnace to which the invention is applied comprises an ash pit 5, a stoker grate 6 comprising a plurality of tiltable bars positioned above the ash pit and supported by 100 the rear wall 7 of the ash pit, and the transversely extending support 8 at the forward end of the furnace.

The front wall of the furnace comprises a projecting portion 9 preferably made of 105 channel iron and a portion comprising the plates 14 and 15 substantially in vertical alignment with the forward end of the stoker, thus providing an offset or horizontally extending shelf-like portion 11 be-

tween the two parts of the front wall of the furnace, said portion 11 being preferably in the form of a metallic plate.

Between the plate 11 and the member 8 are 5 provided the bricks 12 of refractory material and the block 13 of refractory material, providing a fire proof wall portion between said members 8 and 11. The plate 15 is secured to the plate 14 by bolts 10 and has the 10 lip or flange 16 at the lower end thereof.

The furnace is provided with a flat arch comprising blocks 17 of refractory material immediately to the rear of the front of the furnace and the plate 15 terminates a short 15 distance above the bottom of the arch, thus providing an opening 18 between the bottom of the plate 15 and the plate 11. The blocks 17 are provided with dovetail openings for receiving the holding bar or rod 19 and are 20 put in place by slipping the same on from the front of the furnace. The plate 15 is made removable for the purpose of removing 25 said blocks. Above the shelf-like portion 11 is provided a hopper having the brick side walls 26 and the removable front wall 20, the plates 14 and 15 forming the rear wall of said hopper.

The front plate 20 is provided with a pair 30 of angle irons 21 forming pockets in which the slideable bolts 23 (see Fig. 2) rest, said bolts being provided with handle portions 24 to manipulate the same. The bolts 24 extend into sockets 25 in the wall portions 26 at both sides of the furnace.

35 It will be seen that when the plate 20 is in the position shown in Fig. 1 with both the upper and lower bolts 23 in the sockets 25, that the plate 20 will be held rigidly in position while if the upper bolts 23 are 40 withdrawn, the plate 20 will swing about the lower bolts as pivots and will cause the contents of the hopper formed between the front wall of the furnace and the members 15 and 20, to be dumped forwardly of the 45 furnace on to the floor 27.

Mounted on the shelf-like portion 11 is a series of closure members or blocks 28 of refractory material, said blocks each being 50 provided with a socket portion at 29 (see Fig. 3) to receive the head 30 on the bracket member 31 which are each pivotally secured to one of the links 32 which are pivoted at the other end thereof to one arm 33 of the bell crank lever 34, said bell crank lever 55 having the other arm 35 thereof made in the form of a socket to receive the operating lever 36. The arm 33 of the bell crank lever is provided with a perforated ear 37 to receive the adjustable stop member 38 which 60 is adapted to engage the projecting wall portion of the furnace as shown in Fig. 1 to limit the inward movement of the blocks 28. The blocks 17 are of the same contour as the blocks 28 and member 19 holds these in 65 the same way as the head 30.

It will be seen that the blocks 28 effectually close the opening 18 in the front wall of the furnace and that as the blocks 28 move over the member 11 toward the opening in the front wall of the furnace, the 70 fuel 39 will be forced on to the stoker 6 to form a pile at 40 where the same will be coked. The members 28 being relatively large and of refractory material, will prevent the burning back of the fuel into the 75 hopper and act as a seal for the opening in the front wall of the furnace.

The blocks 28 are provided with metallic cover plates 41 which are secured thereto by means of screws passing through the openings 42 in the head 30 of the link 31, said plates serving to hold the heads in position in the blocks, and also to break up any large lumps of coal that may wedge between a block 28 and a block 17. The blocks 28 can be 80 readily removed when desired by swinging the lever 36 downwardly to the dotted position shown in Fig. 1, when the block will be in such position that the plate 41 can be removed and the head 30 can be pulled upwardly out of the socket 29 to detach the block from the link 31. Instead of using the connection shown in Fig. 3, the block can be 85 made as shown in Fig. 4 in which the block 28' is shown as having a cover plate 41' which is secured by means of screws passing through the openings 42' in the end of the member 31' that engages with the block 28'. The block 28' is provided with a pair of 90 grooves at the sides thereof at 43 and the member 31' is provided with a pair of laterally extending members 44 which are provided with right angular portions 45 extending along the sides of the block and with 95 inwardly turned end portions 46 seated in 100 the grooves 43.

The bell crank levers 34 are mounted on a shaft 47 which is circular in cross section so that said members may turn independently of each other so that each of the closure members may be operated independently of the others to push the fuel into the fire box. However, in order to provide for the simultaneous operation of all of the parts by means of a single lever 36, the members 48 are provided which pass through openings in the bell crank lever 34 and are adapted to engage in recesses or socket portions 49 in the shaft 47.

Each section of the stoker grate 6 is operated by a single operating lever 50, there being a stoker grate consisting of two sections used in the form of the device shown in Figs. 1 and 2, it being, of course, understood that any number of sections can be used as desired. Each of the sections is provided with an ash dumping member 51 at the rear thereof which is operated by means of the operating member 52 having a handle 53 thereon for operating the ash dumping 120 125 130

section 51 to dump the ashes into the ash pit at 54.

Having thus described my invention, what I desire to claim and secure by U. S. Letters 5 Patent is:

1. The combination with a furnace of a fuel receiving hopper, the front wall of said furnace serving as the rear wall of said hopper, said wall being provided with an opening and said hopper comprising a pair of fixed end walls and a removable front wall portion and means for holding said front wall portion in position comprising an upper pair of holding members and a lower 15 pair of holding members spaced from the bottom edge of said front wall portion, said members being movable into and out of holding position, whereby said front wall portion is swingable into and out of normal 20 position on said lower pair of members as pivots.

2. The combination with a furnace having a front wall provided with a fuel feeding opening, of a hopper adjacent said front wall having an opening in the bottom thereof closely adjacent said fuel feeding opening, a shelf-like portion below said hopper terminating at its inner end at said fuel feeding opening and substantially in vertical 25 alignment with the inner edge of the opening in said hopper, a stoker grate in said furnace below said fuel feeding opening, whereby fuel is adapted to be fed from said hopper through said openings on to said stoker 30 grate by gravity, pusher members operating over said shelf-like portion and means to actuate said pusher members for accelerating the feeding of fuel to said stoker, said means permitting said pusher members to be positioned so as to collectively seal said fuel 35 feeding opening and close the opening in the bottom of said hopper, and permitting said members to be positioned relative to the opening in the bottom of said hopper to vary 40 the effective size of said opening.

3. A device of the character described, comprising a furnace having an opening in the front wall thereof, a shelf-like portion forwardly of said opening, pusher members operating over said shelf-like portion and adapted to close said opening, links pivotally secured to said pusher members, a shaft, and bell crank levers mounted on said shaft, one arm of each of said bell crank levers being pivoted to one of said links whereby the block associated therewith is moved back and forth on said shelf as said lever is oscillated and a releasable connection between each of said bell crank levers and said shaft 55 whereby said blocks are either independently operable or movable in unison.

4. The combination with a furnace having a front wall provided with a fuel feeding opening, of a hopper adjacent said front wall having an opening in the bottom thereof

closely adjacent said fuel feeding opening, a stoker grate in said furnace below said fuel feeding opening, whereby fuel is adapted to be fed from said hopper through said openings onto said stoker grate by gravity, a shelf-like member below the opening in said hopper, pusher members slideable over said shelf-like portion and means to actuate said pusher members for accelerating the feeding of fuel to said stoker, said means permitting said pusher members to be positioned so as to collectively seal said fuel feeding opening and simultaneously close the opening in the bottom of said hopper and permitting said members to be positioned relative to the opening in the bottom of said hopper to vary the effective size of said opening.

5. The combination with a furnace having a front wall provided with a fuel feeding opening, of a hopper adjacent said front wall having an opening in the bottom thereof closely adjacent said fuel feeding opening, a stoker grate in said furnace below said fuel feeding opening, whereby fuel is adapted to be fed from said hopper through said openings onto said stoker grate by gravity, pusher members for accelerating the feeding of fuel to said stoker grate collectively sealing said fuel feeding opening and closing the opening in the bottom of said hopper, said members being movable across the opening in the bottom of said hopper to vary the effective size of said opening, actuating means for moving said blocks and a detachable connection between each of said blocks and said actuating means.

6. In a furnace having a flat arch of refractory material and having an opening in the front wall thereof adjacent said arch, a closure for said opening comprising a plurality of substantially rectangular adjoining reciprocable fuel pusher blocks of refractory material movable into position with their forward ends engaging said arch and their sides in engagement to collectively close said opening and means for moving said blocks into and out of closing position.

7. The combination with a furnace having a front wall provided with a fuel feeding opening, of a hopper adjacent said front wall having an opening in the bottom thereof closely adjacent said fuel feeding opening, a stoker grate in said furnace below said fuel feeding opening, whereby fuel is adapted to be fed from said hopper through said openings onto said stoker grate by gravity, pusher members for accelerating the feeding of fuel to said stoker grate collectively sealing said fuel feeding opening and closing the opening in the bottom of said hopper, said members being movable across the opening in the bottom of said hopper to vary the effective size of said opening, actuating means for moving said blocks, a

detachable connection between each of said blocks and said actuating means and a quick detachable handle on said actuating means.

8. The combination with a furnace, of a stoker grate, a hopper having an opening in the bottom thereof adapted to supply fuel to said stoker grate by gravity and pusher members for accelerating the feeding of fuel to said stoker grate, said pusher members collectively sealing the fuel opening of the furnace and being movable across the opening in the bottom of said hopper to vary the effective size of said opening, said pusher members having means for operating the same whereby said pusher members are either independently movable or movable as a unit.

9. The combination with a furnace having a front wall provided with a fuel feeding opening, of a hopper adjacent said front wall having an opening in the bottom thereof closely adjacent said fuel feeding opening, a shelf-like portion below said hopper terminating at its inner end at said fuel feeding opening and substantially in vertical alignment with the inner edge of the

opening in said hopper, a stoker grate in said furnace below said fuel feeding opening, whereby fuel is adapted to be fed from said hopper through said openings onto said stoker grate by gravity, and pusher members operating over said shelf-like portion and means to actuate said pusher members for accelerating the feeding of fuel to said stoker, said means permitting said pusher members to be positioned so as to collectively seal said fuel feeding opening and close the opening in the bottom of said hopper, said means permitting said members to be positioned relative to the opening in the bottom of said hopper to vary the effective size of said opening, said stoker grate being positioned a substantial distance below said fuel feeding opening closely adjacent the front wall of said furnace to permit a pile of fuel of substantial depth to accumulate on the forward end of said stoker grate to coke the same.

In witness whereof, I hereunto subscribe my name this 11th day of August A. D., 1921.

GEORGE A. KOHOUT.
